Specification for Design.

Patented Apr. 26, 1921.

Application filed April 21, 1919. Serial No. 291,750. Term of patent 14 years.

To all whom it may concern:

Be it known that I, ADOLPH K. BRAUER, a citizen of the United States, residing at Los Angeles, in the county of Los Angeles and State of California, have invented a new, original, and ornamental Design for Sprinkler-Bodies, of which the following is a specification, reference being had to the accompanying drawing, forming part thereof.

Figure 1 is a side elevation of the sprinkler body, showing my new design.

Fig. 2 is a plan view of the same.
Fig. 3 is a view from the right of Fig. 1.
Fig. 4 is a bottom view.

This design is adapted for the bodies of sprinklers having covers not shown.

I claim:

The ornamental design for a sprinkler body substantially as shown.

ADOLPH K. BRAUER.
